SEWING MACHINE

Michael McCann, St. Albans, N. Y., assignor to
 Frederick Osann Company, New York, N. Y., a
 corporation of New York

Application April 9, 1930. Serial No. 442,723

9 Claims. (Cl. 112—122)

The present invention relates in general to the construction and mode of operation of sewing machines, and particularly, of sewing machines including mechanisms for trimming an edge of 5 one or more plies of material and sewing the trimmed edges together.

The general object of my present invention is to provide a sewing machine of this type having an improved construction, arrangement, and 10 mode of operation of the trimming mechanism. A further object is the provision of a sewing machine incorporating a special form of binding tape folding mechanism in an improved arrangement in the machine relative to my improved trimming mechanism and the stitching mechanism, all of which are arranged to jointly provide a piece of material with a uniformly bound edge portion. A further object is the provision of a 15 sewing machine trimming mechanism with an improved construction and arrangement of the trimming knife operating connections and an improved construction of the mechanism for throwing the trimming knife into and out of operation. A further object is the provision of a sewing machine trimming mechanism with improved means for guiding the movements of the trimming knife during its operation. A further object is the provision of a sewing machine presser foot with means cooperating with portions of the trimming 20 mechanism in effectively disposing of the material removed by the trimming knife. A further object is the provision of a sewing machine of the above described character which is simple, compact, positive in operation, and which efficiently attains the objects above set forth.

The various features of novelty which characterize my invention are further pointed out in the claims annexed to and forming a part of this specification. For a better understanding 40 of the invention, however, and the advantages possessed by it, reference should be had to the accompanying drawings and descriptive matter in which I have illustrated and described a preferred embodiment of the invention.

Of the drawings:—

Fig. 1 is an elevation of the outer end of the machine with the head plate removed to more clearly show certain portions of the operating mechanism, and with the needle bar and trimming knife in their uppermost operative position;

Fig. 2 is a front elevation of the head with the front side of the head casing broken away to 55 show a front view of the mechanism illustrated

in Fig. 1, with the trimming mechanism in its inoperative position;

Fig. 3 is a front elevation of a portion of the mechanism shown in Fig. 2, with the trimming mechanism in its uppermost operative position; 60

Fig. 4 is a view similar to Fig. 1, illustrating the trimming mechanism in detail;

Fig. 5 is a horizontal section on the line 5—5 of Fig. 2;

Fig. 6 is a horizontal section on the line 6—6 65 of Fig. 3;

Fig. 7 is an enlarged front elevation partly in section of the trimming knife guide block arrangement; and

Fig. 8 is a horizontal section on the line 8—8 70 of Fig. 2 with the presser foot omitted for purposes of clarity.

While the present improvements are adapted to be incorporated and used in various well known types of lock stitch and chain stitch sewing machines, they are especially adapted for use in sewing machines of the rotary hook type and are hereinafter described in connection with a machine of this type. Many of the parts of the machine illustrated are or may be similar, or substantially similar, to those of this type of sewing machine as heretofore constructed, and for these parts, other parts, different in form but similar in function, may be readily substituted. Among such parts are an overhanging hollow arm A, a 80 vertically elongated hollow head A' integrally formed at the outer end of the arm A and having its open outer end closed in the usual manner by a head plate (not shown), a bed plate A², a needle plate A³ containing the usual needle opening A⁶, 85 a needle bar A⁴ carrying an eye-pointed needle A⁵, and a presser bar A⁷. The presser bar A⁷ and needle bar A⁴ are arranged for vertical reciprocation in sleeve bearings A⁸ located in and extending through corresponding openings in the lower end 90 of the head. A main upper drive shaft B extends axially in the arm A with its outer end portion journalled in a partition A⁹ separating the interiors of the arm and head. The outer end of the shaft B carries an eccentric B', as shown, 100 from which a crank pin B² projects outwardly. A pitman B³, extending downwardly adjacent the outer face of the eccentric B', is pivotally connected to the pin B² and to a lateral arm B⁴ of a clamp B⁵, which is secured to the upper end of 105 the needle bar, and by which parts the usual needle and needle bar reciprocating movements are effected and controlled. A well known form of hand lever B⁶ for raising and lowering the presser bar A⁷ in opposition or conjunction, re-

110

spectively, with a coiled spring B⁷ is also illustrated. A take-up rod C is also driven from the main shaft B. The take-up drive includes a crank C' and a crank pin C², the latter being pivotally connected to a sleeve C³, which is slideably mounted on the take-up rod C, and all of which collectively effect oscillatory movements of the rod. The take-up rod is formed with a lateral end section C⁴ having the usual thread opening C⁵ and 10 extending through a curved slot in the head plate.

As stated heretofore, the improvements are 15 preferably incorporated in a rotary hook sewing machine, because of the high speeds possible in this type and its capacity for incorporating the improvements evolved without materially reducing the speed of operation. The machine includes a rotary hook shaft D, preferably driven from the main drive shaft B through suitable driving connections mounted in the machine standard. A rotary hook D⁶ is carried at the head end of the shaft D and constructed to receive a bobbin and bobbin case in the usual manner. The bobbin case is removably held in its operative position by a cup-shaped disc D', swingable outwardly on 20 pivots D² to permit the insertion and removal of the bobbin structure. A latch D³ holds the disc in its normal operating position. A cloth feed D⁴ extends through openings in the needle plate and is actuated through eccentrics from shafts 25 D⁵, at each side of and operatively connected to the shaft B.

The trimming mechanism, as preferably constructed in accordance with the present invention, comprises a vertically reciprocable trimming 30 knife E in the form of a flat faced vertically elongated blade having a lower cutting edge E' formed, as shown best in Figs. 1, 4 and 7, with successive inclined portions E² and E³ extending forwardly from a substantially pointed rear end. The knife 35 is preferably positioned a substantial distance forwardly and slightly inwardly of the needle A⁵.

The knife E is provided with a vertical slot E⁴ in its upper end, which is vertically slideable in, and held against forward or rearward movements 40 by, side flanges E⁵ formed on a knife block E⁶. A screw E⁷, extending through the slot E⁴ and engaging the block E⁶, holds the knife in any desired vertical position. As shown in Figs. 1, 2 and 4, the knife block E⁶ is formed at its inner side with 45 a horizontal tongue E⁸ extending substantially throughout its entire length and slidably fitting in the groove formed by a pair of vertically spaced horizontal flanges F' on the forward end of a knife carrier F. The desired horizontal position 50 of the block E⁶ in the groove is maintained by a screw F² extending through a horizontal slot F³ in the carrier into engagement with the block. By the foregoing provisions, the vertical and horizontal positions of the trimming knife in the 55 vertical plane of its body relative to the carrier F and adjacent machine parts can be readily adjusted for varying operating conditions.

Substantially similar adjusting means are provided for the connection between the knife carrier 60 F and a vertically reciprocable knife bar H. As shown in Figs. 3, 4 and 6, the carrier F has a vertically and laterally extending body portion F⁴ provided with a horizontal tongue F⁵ slideably fitting into the groove formed by a pair of vertically 65 spaced horizontal flanges H' on the knife bar mechanism and held in any desired position by a screw F⁶ and slot F⁷, as described heretofore. The flanges H' are formed at the front side of a clamping member H², the legs H³ of which surround and are secured to the lower end of the 70

knife bar H by a bolt H⁴. The knife carrier and thereby the knife are thus arranged for horizontal and vertical adjustments relative to the knife bar. An operating finger F⁸ projects inwardly from the carrier.

The parts of the trimming mechanism heretofore described are arranged to be operatively connected to the drive shaft B for vertical reciprocating movements similar to and synchronized with those of the needle bar. The trimming mechanism drive connections include an eccentric G on the shaft B between the partition A⁹ and the inner side of the needle bar eccentric B'. A strap G² encircles the eccentric and carries a depending arm G³, which is pivotally connected to a horizontal pin G⁴. The pin G⁴ is rigidly mounted in a clamp member G⁵, which is arranged to be operatively connected or disconnected from the knife bar H by a throw-in-and-out mechanism. The inner side of the head is cut away as shown in Fig. 2 to permit the driving parts to be positioned therein and to move as is hereinafter described.

The throw-in-and-out mechanism, as shown in Figs. 2 to 5, consists of a horizontal tubular casing J of relatively small diameter and from the outer end of which the clamp G⁵ projects vertically. A plunger J' is axially movable in the casing J towards its operative or engaging position by the action of a coiled compression spring J² surrounding the plunger stem and to an inoperative or disconnected position by the manual operation of an angular finger J³, which is detachably connected to the inner end of the plunger. The horizontal section of the finger J³ contacts with the flattened inner end of the casing J. The knife bar H carries a block K, of the general form shown in Fig. 5 and incorporating clamping parts K³ by which it is secured to the upper end of the bar. The block K has a forwardly extending section K' terminating in a vertical inner face K⁸ at the outer side of and adjacent to the outer end of the casing J. A horizontal recess K² is formed across the face K⁸ and into which the slabbed outer end J⁹ of the plunger J' is arranged to automatically move when the parts are in horizontal alignment to operatively connect the drive shaft B and knife bar H. When the plunger J' is withdrawn from the recess K² by operating the finger J³, it is evident that the knife 105 bar and drive shaft will be disconnected and no further movement of the knife bar can occur until the parts are restored to engagement.

As shown particularly in Figs 1 and 5, the parts of the throw-in-and-out mechanism shown 110 as connected to the drive shaft B are moved vertically whenever the shaft B is rotated and irrespective of the knife bar connection. The vertical movement of these parts is guided and controlled by a rocker arm J⁴ integrally connected to 115 and extending rearwardly from the plunger casing J. The rear end of the arm J⁴ is formed with a hub J⁵, which is rotatably mounted on a horizontal pin J⁶ clamped in a bracket J⁷ on the rear side of the head A'. By the foregoing provisions, 120 the plunger J' is maintained during its disconnected vertical movements in contact with the face K⁸.

With the described construction and arrangement, the plunger would necessarily return to its 125 position in the recess K² whenever the finger J³ is released unless the recessed portion of the face is held out of the path of movement of the plunger. Automatic means for this purpose are provided and comprise a post K⁴ mounted in the 130

- lower end of the head and extending vertically through an opening K^5 in the block K . A spring K^6 is coiled about the post K' between the lower face of the block K and the head. The spring K^6 is under compression at all times when the knife bar is being operated and, when the plunger J' is withdrawn, automatically raises the recess K^2 above the range of movement of the plunger on the face K^8 . 5
- 10 The knife bar may be returned to a lower engaging position by the operator depressing the finger F^8 , at which position the plunger will automatically enter the recess K^2 and again connect the knife bar to the shaft B . To insure engagement of the plunger and block during this movement, the portion of the block determining the upper face of the recess K^2 is extended to form an inwardly projecting shoulder K^7 , which as shown in Fig. 1, prevents the movement of the block K downwardly by the operator past the plunger engaging position. The limiting action is effected by the shoulder abutting the upper surface of the outer end of the plunger. The plunger will thus snap into the recess and operatively connect the knife bar and drive shaft whenever the finger F^8 is depressed. 15
- 20 As shown particularly in Figs. 2, 3, 6, and 8, the trimming mechanism also includes a stationary knife M , horizontally arranged in a recess M' in the upper surface of the needle plate A^3 at a point in front of the needle and is provided with a rearwardly extending cutting edge M^2 which cooperates with the knife E . The knife M is held against movement by the edges 30 of the recess M' and by a screw M^3 engaging the needle plate. The portion of the needle plate and bed plate inwardly of the cutting edge of the knife M is cut away, as shown in Figs. 2, 6, and 8, to permit the insertion therein of a guard member N for disposing of the cuttings removed from the material by the trimming knives. 35
- 40 The guard N is constructed with a horizontal lip N' resting on the bed plate inwardly and in front of the knife M , a depending substantial rectangular cutting receiving section N^2 below the cutting edge of the fixed knife M and having an outer vertical wall N^3 contacting with the lower face of the blade M adjacent its cutting edge, a vertical rear wall N^4 extending upwardly adjacent the rear edge of the knife E , and a horizontal bottom plate N^5 terminating in an inclined apron section N^6 . The rear wall N^4 extends upwardly above the surface of the bed plate with its outer corner portion terminating in a forwardly extending cutting deflecting section N^7 , the lower edge N^8 of which extends substantially horizontally alongside of the inner face of the blade E . The guard N is held in position on the bed plate by screws N^{10} passing through short horizontal slots N^{11} , which permits a limited lateral adjustment of the guard. 50
- 55 Associated with the guard member and other parts described is a presser foot O adjustably and detachably mounted on the lower end of the pressed bar A^7 and adapted to be raised and lowered therewith by the lever B^6 . The presser foot proper is of a well known form, with the addition of a guard O' having a lateral arm O^2 mounted on the upper side of the inclined end of the presser 65 foot and horizontally adjustable thereon by a horizontal slot O^3 and screw O^4 . The guard O' extends alongside the inner edge of the foot in front of and substantially in vertical alignment with the knife E , and with its inclined lower edge 70 O^5 slightly spaced from the upper surface of the
- knife M when the presser foot is in its lower or operating position. The guard O' is formed with a laterally off-set section O^6 extending rearwardly between the inner face of the knife E and the edge N^8 of the guard N and substantially closing the space at the inner side of the trimming knives, and whereby the cuttings or clippings removed by the knives are prevented from passing rearwardly over the fixed knife and being subsequently sewed on the material. Normally, the clippings drop into the guard section N^2 and slide down the apron N to deposit in a suitable receptacle or on the floor below the machine. 80
- 85 It is particularly important that the cutting edges of the trimming knives be maintained in a fixed relative position irrespective of the character or quantity of the material operated on. The trimming knife M is fixed in the recess M' and a guide block P is provided for preventing any inward deflection of the knife E . As shown in Figs. 3, 4, 6, and 7, the guide block P is in the form of a channel having vertically spaced horizontal flanges P' arranged to slidably fit on a short horizontal bar P^2 , which is secured to the rear wall N^4 of the guard N in any suitable manner adjacent to the inner face of the knife E . The guide block has a short horizontal slot P^3 through which a screw P^4 extends into engagement with the bar P^2 , providing a limited horizontal adjustment of the block. The outer end of the block 90 may be thus positioned to contact with the inner face of the knife E during its reciprocatory movements and insure a close contact between the movable and fixed knives in operation. 95
- 100 A binding tape folding device R is advantageously associated with the trimming and stitching mechanism heretofore described. The tape folding device utilized is of a well known form and is arranged in a surface recess R' in the needle plate with its outer end extending into an arcuate recess O^7 , formed in the inner side of the presser foot immediately before a needle opening O^8 in the latter. A binding tape of the proper width is inserted in the inner expanded end of the device and withdrawn through an arcuate 105 opening R^2 having reversely curved end portions R^3 in the outer contracted end, whereby the tape is folded along its longitudinal center line and its edge portions folded outwardly. As the tape passes out of the folder, it is turned rearwardly through a semi-circular recess R^3 which causes the main fold of the tape to be reversed and the previously folded edge portions to be turned inwardly. The material, after being trimmed to the extent desired, passes between 110 the main folds of the tape and then, with the binding tape in position, is moved by the cloth feed under the rear portion of the presser foot where the material plies and the tape folds are stitched in the usual manner. The folder R has 115 a horizontal rear extension R^5 , which includes a transverse slot R^6 through which a screw R^7 passes into engagement with the needle plate and by which arrangement, the folder may be moved laterally relative to the needle to thereby 120 regulate the position of the tape relative to the trimmed edge of the material. Other forms and sizes of folders may be readily substituted for the folder illustrated. A short vertical guard O^9 on the presser foot adjacent the needle opening O^8 125 assists in maintaining the binding tape in its desired position relative to the material. An inclined slot N^9 is formed in the rear wall of the guard N and through which the operator can 130 insert a suitable tool into a corresponding slot 135 140 145 150

R⁴ in the folder to assist the initial passage of the tape through the folder R.

The construction and general mode of operation of the machine and particularly of the improvements described is evident from the foregoing description. The movements of the knife E, needle A⁵, feed D⁴ and rotary hook D' are synchronized and effect a high speed trimming and binding operation on the material. As the surplus material is trimmed from the cloth, it is quickly disposed of and prevented from returning into the path of operation by the various guard members. The cutting position and extent of the cutting stroke of the movable knife can be easily regulated within certain limits for different conditions of operation. The employment of a vertically reciprocable knife and the driving connections described provide a highly compact, simple and effective trimming mechanism, and permit the inclusion of substantially all of the movable driving parts within the head. The relative arrangement of the trimming knives, folder, and stitching mechanism described is particularly advantageous, enabling the operator to observe the successive operations with ease, while maintaining the range of movement and positions of the parts in the restricted space available. The described construction of the knife bar driving connections effects a positively operating arrangement, which may be thrown in and out of operation by the operator without loss of time due to improper or inoperative connections. The adjustable knife guide insures the necessary close contact between the stationary and movable knives in operation.

In the foregoing description the words "front", "rear", "inner", and "outer" and corresponding terms have been repeatedly referred to in describing the construction and location of the various parts. These terms are used relative to the position of the operator, i. e., the "front" and "rear" sides of the machine are, respectively, adjacent to and opposite from the operator, while "inner" and "outer" refer, respectively, to points toward the standard and head ends of the machine.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent is:—

60 1. In a sewing machine having an overhanging arm, an enlarged head at the outer end of said arm and a needle plate arranged below said head, the combination with a drive shaft axially arranged in said arm, of a fixed trimming knife associated with said needle plate, a vertically reciprocable needle and needle bar, mechanism operatively connecting said needle bar and drive shaft, a cooperating vertically reciprocable trimming knife positioned in front of and at one side of said needle, an eccentric mounted on said drive shaft at the inner side of said mechanism, a vertically reciprocable knife bar, and mechanism substantially included in said head operatively connecting said eccentric and knife bar.

75 2. In a sewing machine having an overhanging

arm, an enlarged head at the outer end of said arm and a needle plate arranged below said head, the combination with a drive shaft axially arranged in said arm, of a fixed trimming knife associated with said needle plate, a vertically reciprocable needle and needle bar, mechanism operatively connecting said needle bar and drive shaft, an eccentric mounted on said drive shaft at the inner side of said mechanism, a vertically reciprocable knife bar mounted in the lower end of said head in the rear of said needle bar, mechanism operatively connecting said eccentric and knife bar, a knife carrier vertically and horizontally adjustable on the lower end of said knife bar and extending forwardly of said needle, and a vertically arranged trimming knife vertically and horizontally adjustable in said carrier forwardly of said needle and cooperating with said fixed knife.

3. In a sewing machine having an overhanging arm, an enlarged head at the outer end of said arm, and a needle plate arranged below said head, the combination with a drive shaft axially arranged in said arm, of a vertically reciprocable needle and needle bar eccentrically connected to said drive shaft, a fixed trimming knife associated with said needle plate, a cooperating vertically reciprocable trimming knife, a vertically reciprocable knife bar connected to said movable knife, an eccentric mounted on said drive shaft at one side of said needle bar eccentric, mechanism operatively connecting said second eccentric and knife bar, said movable knife being arranged substantially in front of said needle, and a vertical guard member associated with said trimming knives and arranged to deflect and dispose of the material removed by said knives.

4. In a sewing machine having an overhanging arm, an enlarged head at the outer end of said arm, and a needle plate arranged below said head, the combination with a main drive shaft axially arranged in said arm, of a fixed trimming knife associated with said needle plate, a cooperating vertically reciprocable trimming knife, means operatively connecting said reciprocable trimming knife and said drive shaft, a presser foot at one side of said reciprocable knife, and a guard member carried by said presser foot and extending along and adjacent to the cutting edge of said fixed knife.

5. In a sewing machine having an overhanging arm, an enlarged head at the outer end of said arm, and a needle plate arranged below said head, the combination with a main drive shaft axially arranged in said arm, of a fixed trimming knife associated with said needle plate, a reciprocable needle and needle bar, a vertically reciprocable trimming knife at the inner side of and in front of said needle, means for operatively connecting said reciprocable trimming knife and said drive shaft, a presser foot at the outer side of said reciprocable knife, and a guard adjustably mounted on the forward end of said presser foot and extending rearwardly along the inner face of said reciprocable knife.

6. In a sewing machine having an overhanging arm, an enlarged head at the outer end of said arm, and a needle plate arranged below said head, the combination with a main drive shaft axially arranged in said arm, of a fixed trimming knife associated with said needle plate, a cooperating vertically reciprocable trimming knife, means operatively connecting said reciprocable knife and said drive shaft, a vertical guard member extending transversely to and adjacent the rear

- edge of said reciprocable knife, a presser foot at one side of said reciprocable knife, and a second vertical guard member carried by said presser foot and extending along and adjacent to the cutting line of said knives and cooperating with said first mentioned guard member to guide the material cut off by said knives. 80
7. In a sewing machine having an overhanging arm, an enlarged head at the outer end of said arm, and a needle plate arranged below said head, the combination with a main drive shaft axially arranged in said arm, of a fixed trimming knife associated with said needle plate, a cooperating vertically reciprocable trimming knife, means operatively connecting said reciprocable trimming knife to said drive shaft, a vertical guard member adjacent to and at one side of said reciprocable trimming knife, and an adjustable knife guide block mounted on said guard member with its outer end arranged to contact with the inner face of said reciprocable trimming knife during the reciprocating movements of the latter. 85
8. In a rotary hook sewing machine having an overhanging arm, an enlarged head at the outer end of said arm, a needle plate arranged below said head, and a rotary hook and hook shaft below said needle plate, the combination with a drive shaft axially arranged in said arm, of a vertically reciprocable needle and needle bar eccentrically connected to said drive shaft, a fixed trimming knife associated with said needle plate, a cooperating vertically reciprocable trimming knife, a vertically reciprocable knife bar adjustably connected to said movable knife, an eccentric mounted on said drive shaft at one side of said needle bar eccentric, mechanism operatively connecting said second eccentric and knife bar, said movable knife being arranged substantially in front of said needle, a vertical guard member associated with said trimming knife and arranged to deflect and dispose of material removed by said knives, a binding tape folding device positioned at the rear side of said guard member with its tape outlet end in front of said needle, and registering openings in said guard member and folding device for the insertion of a tape advancing tool. 90
